ADOLPH PETZOLD, OF PHILADELPHIA, PENNSYLVANIA, ASSIGNEE TO JOHN H. BROMLEY AND EDWARD BROMLEY, OF PHILADELPHIA, PENNSYLVANIA, COPARTNERS TRADING AS JOHN BROMLEY & SONS.

DESIGN FOR A RUG.

SPECIFICATION forming part of Design No. 35,252, dated October 29, 1901.

Application filed September 30, 1901. Serial No. 77,152. Term of patent 8½ years.

To all whom it may concern:

Be it known that I, ADOLPH PETZOLD, a citizen of the United States, residing at the city of Philadelphia, State of Pennsylvania, have 5 invented and produced a certain new and original Design for a Rug, of which the following is a full, clear, and exact description, reference being had to the accompanying drawing, forming a part of this specification.

My design is applicable to and intended for the surface ornamentation of woven rugs. In its essentials it consists, as shown in the drawing, of a rectangular border composed of a series of figures *a* and *b*, arranged between two parallel line-figures *c* and *d*. The

field center is occupied by a figure having outline ends *e*, each converging to a blunt point, the central space being occupied by a series of ornamental figures.

I claim—

The design for a rug, substantially as shown and described.

In testimony whereof I have hereunto affixed my signature this 13th day of August, A. D. 1901.

ADOLPH PETZOLD.
